UNITED STATES PATENT OFFICE.

WALTER ALEXANDER SINZ, OF CLEVELAND, OHIO, ASSIGNOR TO R. GUY COWAN, OF LAKEWOOD, OHIO.

DESIGN FOR A FLOWER HOLDER.

Application filed March 29, 1926. Serial No. 17,097. Term of patent 7 years.

To all whom it may concern:

Be it known that I, WALTER ALEXANDER SINZ, a citizen of the United States, residing at 6013 Olive Court, Cleveland, in the county of Cuyahoga and State of Ohio, have invented a new, original, and ornamental Design for a Flower Holder, of which the following is a specification, reference being had to the accompanying drawing, forming part hereof.

The figure is a perspective view of a flower holder showing my new design.

I claim:

The ornamental design for a flower holder, as shown.

WALTER ALEXANDER SINZ.
